DISPENSING APPARATUS

Filed June 29, 1921

INVENTOR
John B. Davis
BY Chas. J. Neal
ATTORNEY

UNITED STATES PATENT OFFICE.

JOHN B. DAVIS, OF SPRINGFIELD, MASSACHUSETTS, ASSIGNOR TO GILBERT & BARKER MANUFACTURING COMPANY, OF WEST SPRINGFIELD, MASSACHUSETTS, A CORPORATION OF MASSACHUSETTS.

DISPENSING APPARATUS.

Application filed June 20, 1921. Serial No. 478,977.

To all whom it may concern:

Be it known that I, JOHN B. DAVIS, citizen of the United States, residing at Springfield, in the county of Hampden and 5 State of Massachusetts, have invented new and useful Improvements in Dispensing Apparatus, of which the following is a specification.

This invention relates to improvements 10 in power-operated dispensing pumps, such, for example, as those used for the dispensing of gasoline and other oils.

The power-operated dispensing pumps, as far as I am aware, move at a fixed speed and, 15 once the power is applied, the pump piston moves substantially uniformly throughout its stroke or until the power is disconnected. This arrangement has a disadvantage over hand operation, where the pump piston may 20 be caused to move as slowly as desired. Thus, it frequently happens that the purchaser wishes to fill a tank and yet is doubtful whether it will hold the entire quantity dispensed at one stroke of the pump. In 25 such cases, the purchaser naturally watches the tank and, as it becomes nearly filled, instructs the operator of the dispensing pump to pump slowly and be ready to stop at an instant's notice. With the power-operated 30 pump, as generally provided, the above condition cannot be met and there is danger of overflowing the tank.

This invention has for its object to provide in a power-operated dispensing pump, 35 means for retarding the speed of the pump as and when desired.

It is a further object of the invention to provide a braking device which is manually operable when desired to retard and even 40 stop the pump.

Other objects and advantages will appear in the following description and in the illustrative embodiment of the invention in the accompanying drawings, in which,—

45 Fig. 1 is an elevational view, partly in section, of a dispensing pump, embodying the invention;

Fig. 2 is an enlarged fragmentary plan view of the speed controlling device;

Fig. 3 is a sectional view thereof, taken 50 on the line 3—3 of Fig. 2;

Fig. 4 is a detail view partially in elevation and partially in vertical section of the control valve; and

Fig. 5 is a view, in vertical section of a 55 portion of the pump cylinder, showing the pump piston.

Referring to these drawings; there has been shown, as an illustrative example, one type of power-operated dispensing apparatus to which my invention may be applied. 60 As shown, such apparatus includes a pump cylinder 5 mounted between upper and lower header members 6 and 7, respectively. On opposite sides of cylinder 5, and mounted between the header members 6 and 7, are other smaller cylinders 8, to which fluid under pressure may be admitted. A piston 9 is provided in each cylinder and, from the pistons, piston rods 10 extend upwardly 65 through the header member 6 and are connected together by a cross-head 11. A piston rod 12 for pump cylinder 5 is connected to the cross-head 11 intermediate the ends of the latter, and descends through the 70 header member 6 into cylinder 5, where it is provided with a suitable piston 5^a.

Each piston rod 10 is guided in a bracket 13, fixed to header member 6, as shown in Fig. 2, and also has teeth 14 cut in one face 80 thereof, forming a rack. In mesh with each rack, thus formed, is a gear 15, partially housed within the bracket 13. These gears 15 are fixed in longitudinally spaced relation on a shaft 16, mounted in the brackets 85 13 and having fixed near one end a clutch element 17 and carrying loosely a crank handle 18, having a mating clutch element 19. Thus, by pushing handle 18 inwardly 90 to engage the clutch elements 17 and 19, the shaft 15 may be rotated by manually turning the crank handle, whereby the piston rod 12 may be reciprocated. Normally, however, the elements 17 and 19 are disengaged, as shown.

The cylinders 8 are connected together near their bases by a pipe 20 and from the latter a pipe 21 extends vertically upwardly 95

to a suitable valve 22 operable by a suitable lever 23, said valve and lever being shown in detail in Fig. 4. A pipe 24 leads from the valve 22 to a suitable source of fluid under pressure. The valve 22 is so arranged as to normally connect pipe 21 to atmosphere and, with this condition, the weight of parts connected to piston rod 12 is sufficient to cause the latter to move downwardly to its lower limit. A depression of lever 23 will operate the valve so as to connect pipes 21 and 24, whereby fluid under pressure will be admitted simultaneously to cylinders 8, thereby lifting the racks 10 and piston rod 12 and 15 incidentally rotating shaft 16.

The dispensing apparatus may, as shown, be encased, as by lower, intermediate, and upper casings, 25, 26, and 27, respectively. The casing 27 may carry a suitably graduated scale 28 over which plays a pointer 29, the latter being fixed to a rod 30 carried by cross-head 11.

The means for controlling the speed of the pump piston rod 12 preferably consists of a braking device, one example of which is shown in Fig. 3. The device there shown consists of a drum 31 suitably fixed to shaft 16 and a brake band 32 with means for applying the latter to the former. As shown, drum 31 is made in two parts clamped together by bolts 33, simply for convenience in applying it to existing pumps. The band 32, preferably provided with a suitable lining 34, has loops 35 and 36 formed at its ends and the band is slotted at its ends through these loops, as indicated at 37 in Fig. 2. The loop 35 slips over a pin 38 projecting from bracket 13 and is held from axial movement by a screw 39, which passes loosely through pin 38 and through slot 37 and is provided with an adjusting nut 40. On the lower end of screw 39 is a fork 41 in which is pivoted a lever 42. One end of the latter is received in the slot in loop 36 and is pivotally connected thereto by a pin 43 passing through the loop and lever. On a depression of the free end of lever 42, to force band 32 about the drum 31, the pressure on fork 41 is downwardly and consequently it is not necessary to fix screw 39 in pin 38.

In operation, the lever 23 is depressed, whereby the pistons 9 lift the piston rod 12 at a substantially uniform speed. At the same time shaft 16 and drum 31 are set in rotation. In case the operator is instructed to pump slowly, the operator simply depresses lever 42 until the piston rod is retarded to the desired degree and, if necessary, the piston rod may be entirely stopped by the braking device. In any event, the latter permits the operator to control the speed of the piston rod as desired and particularly according to the desire of the purchaser, whereas with simply the valve 22 it

is very difficult to get the result desired. At best, only an approximation of the result can be obtained by a series of stops and starts and the operator does not have complete control of the situation at all times, as he does with the braking device.

Various other means may be provided for retarding the speed of the piston rod and such means may be used with various other styles of power-operated pumps without departing from the scope of the invention. An example of an alternative means for retarding the speed of the pump is disclosed in a copending application Ser. No. 513,369, filed Nov. 7, 1921.

It is to be understood that the scope of the present invention is defined by the appended claims rather than by the foregoing description.

What I claim is—

1. In combination, a pump, automatic means including a rotatable shaft for operating the pump, a controlling device to start and stop the pump, a brake drum on said shaft, a brake shoe for said drum, and means for forcing said shoe against said drum to oppose said automatic means and retard the speed of operation of said pump.

2. In combination, a reciprocating piston pump, pneumatic means for moving the piston rod thereof, a controlling device for said pneumatic means, and braking means operable when desired and independently of said device for retarding the speed of said piston rod when moved by said pneumatic means.

3. In combination, a pump cylinder, a piston rod therefor, a cylinder on each side of the pump cylinder, rack-bar piston rods for said second-named cylinders, means comprising a valve for admitting to and exhausting from the latter fluid under pressure, a cross-head connecting all said piston rods, a shaft, gears thereon in mesh with the rack-bar piston rods, a brake drum on said shaft, a brake band cooperating with said drum, and manually-operable means independent of said valve for applying said band to the drum when desired.

4. In combination, a reciprocating piston pump, mechanism actuated by fluid under pressure for moving the piston rod of the pump in one direction, and means for retarding the speed of said piston rod, when desired without reducing the fluid pressure upon said actuating mechanism.

5. In combination, a reciprocating piston pump, mechanism actuated by fluid under pressure for moving the piston rod of the pump in one direction, and manually operable means for applying resistance in varying degrees to said mechanism to retard the speed of said piston rod without reducing the fluid pressure upon said actuating mechanism.

6. In combination, a pump cylinder, a piston rod therefor, a cylinder on each side of the pump cylinder, rack-bar piston rods for said second-named cylinders, means for admitting to and exhausting from the latter fluid under pressure, a cross-head connecting all of said piston rods, a shaft, gears thereon in mesh with the rack-bar piston

rods, a brake drum on said shaft, a brake member cooperating with said drum, and 10 manually operable means for applying said member to the drum when desired.

In testimony whereof I have affixed my signature.

JOHN B. DAVIS.
